UNITED STATES PATENT OFFICE.

IRA E. SISK, OF EAST ST. LOUIS, ILLINOIS.

BIT-STOCK.

1,171,670.

Specification of Letters Patent. Patented Feb. 15, 1916.

Application filed September 23, 1914. Serial No. 863,194.

To all whom it may concern:

Be it known that I, IRA E. SISK, a citizen of the United States, residing at East St. Louis, in the county of St. Clair and State 5 of Illinois, have invented new and useful Improvements in Bit-Stocks, of which the following is a specification:

This invention relates to wood boring tools, the object of the invention being to 10 provide a tool the construction of which will enable the parts thereof to be associated with each other under different relations adapting the boring bit to be actuated and utilized in otherwise inaccessible and 15 circumscribed places as well as in the ordinary open accessible work.

With the above and other objects in view, the invention consists in the novel construction, combination and arrangement of parts, 20 as herein described, illustrated and claimed.

In the accompanying drawings:—Figure 1 is a plan view, partly in section, of the main staff or stock of the tool; Fig. 2 is a detail perspective view of the adjustable head block including the sprocket wheel and operating crank connected therewith; Fig. 3 is a similar view of the chuck, bearing head and ratchet device; Fig. 4 is a detail view of the presser head; Fig. 5 is a similar 25 view of the ratchet handle; Fig. 6 is a detail view of the detachable brace; Fig. 7 is a side elevation of the complete tool; Fig. 8 shows a combination of parts of the tool for use as a ratchet boring device; and Fig. 9 30 is a view, showing parts combined to form an ordinary ratchet brace.

The tool contemplated in this invention comprises the main staff or stock 1, which is preferably straight from end to end and 40 provided at one end with a detachable breast piece 2 having a socket 3, in which the adjacent end of the staff 1 is received and held by means of a set screw 4. At its opposite end the staff 1 is formed with a square 45 socket or bore 5 and set screw 6, the purpose of said socket to be hereinafter stated.

7 designates the bit holding chuck which is journaled in the usual bearing head 8 and 50 associated with a ratchet device 9 of the ordinary construction, the shank of the chuck 7 being extended above the head 8, as shown at 10, where it is squared to receive a detachable presser head 11, said head embodying a stem 12 having a squared bore or socket 55 13 to receive the shank 10 together with a

set screw 14 for holding said parts in fixed relation to each other.

Fast on the shank 10 of the chuck 7 is a sprocket wheel 15, around which passes a sprocket chain 16, which extends longitudinally of the staff 1 to a point adjacent to the breast piece 2 where it passes around another sprocket wheel 17 journaled on an adjustable head block 18, said head block having a hole through which the staff 1 60 passes and being provided with a screw 19 by which said head block 18 may be held when brought to the proper adjustment. The sprocket wheel 17 is provided with a hand crank 20, whereby it is revolved thereby through the medium of the chain 16 imparting rotary motion to the chuck 7 by means of the sprocket wheel 15.

As will be apparent in Fig. 7, the bearing head 8 is provided with a laterally extending 75 squared shank 21 which is received in the socket 5 in the end of the staff 1 where it is fixed by means of the binding screw 6.

22 designates a ratchet handle having a stem 23 provided with a square bore or 80 socket 24 which is adapted, as shown in Fig. 8, to receive the squared shank 21 of the bearing head 8, thus enabling the device to be used as an ordinary ratchet handle drill or boring device.

25 designates a hand brace of ordinary construction except that the lower normally horizontal arm 26 thereof is provided with a square socket 27 adapted to receive the square shank 21 of the bearing head to adapt 90 the device to be used after the manner of an ordinary hand brace, as shown in Fig. 9.

From the foregoing description, taken in connection with the accompanying drawings, it will now be understood that the 95 parts hereinabove particularly described may be combined in the manner either as shown in Fig. 7, Fig. 8 or Fig. 9. When combined in the manner illustrated in Fig. 7, the boring device is adapted particularly for boring holes through joists where the same are arranged close together or for boring holes in other circumscribed places inaccessible with the ordinary combination shown in Fig. 9. The operating handle 20 in Fig. 7 is located at a considerable distance from the bit carrying chuck but transmits motion thereto through the medium of the sprocket wheels and chain described. Any slack in the chain 16 may be taken up readily 100 105 110 115

by a simple adjustment of the head block 18 away from the bearing head 8. By loosening a single set screw 6 the bearing head 8 may be disconnected from the staff 1 and 5 the actuating chain 16 and either brought into combination with the ratchet handle 22 or the brace 25 as may be found desirable at the time. When used under the combination shown in Fig. 8, the presser head 11 is applied to the square shank 10 of the chuck 7.

I claim:

10 The combination of a bearing head, a bit chuck having a journaled portion extending through and rotatable in the head, a gear wheel fast on said journal portion at the opposite side of the head from the body of the chuck, a ratchet driving member terminating in a shank extending laterally from the

bearing head and perpendicular to the axis on which the chuck journal revolves, said 20 shank being non-circular in cross section, and interchangeable chuck-operating members formed with sockets corresponding in shape with and adapted to receive and hold said shank, one of said operating members 25 embodying a straight stock and straight drive gearing the elements of which together with the above mentioned gear wheel are in a common plane parallel to said stock.

In testimony whereof I affix my signature 30 in presence of two witnesses.

IRA E. SISK.
